US0D1086149S

(12) United States Design Patent (10) Patent No.: US D1,086,149 S
(45) Date of Patent: * Jul. 29, 2025

(54) DISPLAY SCREEN OR PORTION THEREOF WITH A GRAPHICAL USER INTERFACE

(71) Applicant: Aristocrat Technologies, Inc., Las Vegas, NV (US)

(72) Inventors: John Ludwick, Reno, NV (US); Britta Nauta-Larsen, Reno, NV (US)

(73) Assignee: Aristocrat Technologies, Inc., Las Vegas, NV (US)

() Term: 15 Years

(21) Appl. No.: 29/810,013

(22) Filed: Sep. 30, 2021

(51) LOC (15) Cl. 14-04

(52) U.S. Cl.

USPC D14/485

(57) CLAIM

The ornamental design for a display screen or portion thereof with a graphical user interface, as shown and described.

DESCRIPTION

The FIGURE is a front view of a display screen or portion thereof with a graphical user interface according to the new design.

The outermost broken line in the FIGURE illustrates a display screen or portion thereof and forms no part of the claimed design. The remaining broken lines represent elements of the display screen or portion thereof with a graphical user interface that form no part of the claimed design.
